US00D552309S

(12) **United States Design Patent** (10) **Patent No.:** **US D552,309 S**
(45) **Date of Patent:** **** Oct. 2, 2007**

(54) **HANDHELD VACUUM CLEANER**

(75) Inventor: **Stephen Houghton**, Newcastle Upon Tyne (GB)

(73) Assignee: **Black & Decker Inc.**, Newark, DE (US)

(**) Term: **14 Years**

(21) Appl. No.: **29/257,069**

(22) Filed: **Mar. 29, 2006**

(30) **Foreign Application Priority Data**

Oct. 31, 2005 (EM) 000423322

(51) **LOC (8) Cl.** **15-05**

(52) **U.S. Cl.** **D32/18**

(58) **Field of Classification Search** ..... D32/17, D32/18, 21-22, 31; 15/1.52, 1.7, 4, 329, 15/339, 344, 347, 351, 353, 361, 410-412, 15/414, DIG. 1; 55/DIG. 3; D13/107-109, D13/119; 320/115

(57) **CLAIM**

We claim the ornamental design for a handheld vacuum cleaner, as shown and described.

DESCRIPTION

FIG. 1 is a perspective view of a handheld vacuum cleaner showing my new design;

FIG. 2 is a left side view of a handheld vacuum cleaner according to FIG. 1;

FIG. 3 is a right side view of a handheld vacuum cleaner according to FIG. 1;

FIG. 4 is a top view of a handheld vacuum cleaner according to FIG. 1;

FIG. 5 is a bottom view of a handheld vacuum cleaner according to FIG. 1;

FIG. 6 is a front view of a handheld vacuum cleaner according to FIG. 1;

FIG. 7 is a rear view of a handheld vacuum cleaner according to FIG. 1;

FIG. 8 is a perspective view of a handheld vacuum cleaner of FIG. 1 with nose in an extended position;

FIG. 9 is a left side view of a handheld vacuum cleaner of FIG. 1 with nose in an extended position;

FIG. 10 is a right side view of a handheld vacuum cleaner of FIG. 1 with nose in an extended position;

FIG. 11 is a top view of a handheld vacuum cleaner of FIG. 1 with nose in an extended position;

FIG. 12 is a bottom view of a handheld vacuum cleaner of FIG. 1 with nose in an extended position;

FIG. 13 is a front view of a handheld vacuum cleaner of FIG. 1 with nose in an extended position;

FIG. 14 is a rear view of a handheld vacuum cleaner of FIG. 1 with nose in an extended position;

FIG. 15 is a perspective view of a handheld vacuum cleaner of FIG. 1 with nose in an extended position and further showing a telescopic extension;

FIG. 16 is a left side view of a handheld vacuum cleaner of FIG. 1 with nose in an extended position and further showing a telescopic extension;

FIG. 17 is a right side view of a handheld vacuum cleaner of FIG. 1 with nose in an extended position and further showing a telescopic extension;

FIG. 18 is a top view of a handheld vacuum cleaner of FIG. 1 with nose in an extended position and further showing a telescopic extension;

FIG. 19 is a bottom view of a handheld vacuum cleaner of FIG. 1 with nose in an extended position and further showing a telescopic extension;

FIG. 20 is a front view of a handheld vacuum cleaner of FIG. 1 with nose in an extended position and further showing a telescopic extension; and,

FIG. 21 is a rear view of a handheld vacuum cleaner of FIG. 1 with nose in an extended position and further showing a telescopic extension.

FIGS. 8-14 and 15-21 show the nose and telescopic extension in extended positions.
